UNITED STATES PATENT OFFICE.

GUSTAV MUELLER, OF CLEVELAND, OHIO.

DESIGN FOR A MATCH-HOLDER.

No. 40,052.

Specification for Design.

Patented June 15, 1909.

Application filed March 30, 1909. Serial No. 486,839. Term of patent 7 years.

To all whom it may concern:

Be it known that I, GUSTAV MUELLER, a citizen of the United States, residing at Cleveland, in the county of Cuyahoga and State of Ohio, have invented a new and original and ornamental Design for Match-Holders, of which the following is a specification, reference being had to the accompanying drawing, forming part thereof.

The figure is a perspective view of a match holder showing my new design.

I claim:

The ornamental design for a match holder, as shown.

GUSTAV MUELLER.
